UNITED STATES PATENT OFFICE.

HAZEL DRUKKER SILBERMAN, OF NEW YORK, N. Y.

DESIGN FOR A CHILD'S PLAY DRESS.

56,630.

Specification for Design.

Patented Nov. 16, 1920.

Application filed December 13, 1919. Serial No. 344,601. Term of patent 14 years.

To all whom it may concern:

Be it known that I, HAZEL DRUKKER SILBERMAN, residing at the city of New York, borough of Manhattan, county and State of New York, have invented a new, original, and ornamental Design for a Child's Play Dress, of which the following is a specification, reference being had to the accompanying drawing, forming part thereof.

dress, embodying my design, will appear when worn by a child. The essence of my invention resides in the general appearance of the dress having a skirt portion one opening at the bottom for both legs, substantially as shown and described.

It is to be understood that my claim includes all substantial equivalents of my design, as shown and described.

I claim:

The ornamental design for a child's play dress substantially as shown and described.

HAZEL DRUKKER SILBERMAN.
